UNITED STATES PATENT OFFICE.

EDWARD B. PARKHURST, OF WOBURN, MASSACHUSETTS, ASSIGNOR TO POWER NUMBERING MACHINE COMPANY, OF BOSTON, MASSACHUSETTS, A CORPORATION OF MASSACHUSETTS.

STAMPING, MARKING, OR NUMBERING MACHINE.

1,170,490.

Specification of Letters Patent.

Patented Feb. 1, 1916.

Application filed July 22, 1908. Serial No. 444,728.

To all whom it may concern:

Be it known that I, EDWARD B. PARKHURST, a citizen of the United States, residing at Woburn, in the county of Middlesex, State of Massachusetts, have invented a certain new and useful Improvement in Stamping, Marking, or Numbering Machines, of which the following is a specification, reference being had therein to the accompanying drawings.

My present improvement in stamping, marking, or numbering machines has reference to the printing-heads thereof.

It consists in novel means for holding a name-plate or the like detachably in working position upon a printing-head.

My improved means of detachably holding a name-plate or the like in working position upon the printing head in a stamping, marking, or numbering machine is designed, more especially, to enable such plate to be employed when required, and to be removed when not desired to be used, and facilitates the substitution of one plate for another at will.

Having reference to the drawings, Figure 1 is a front view of a printing-head having an embodiment of my invention applied thereto. Fig. 2 is an end elevation thereof with the operating shaft of the printing wheels in section. Fig. 3 is a front elevation of the die-carrying wheel or hub, with one of the dies removed and shown alongside the said wheel or hub. Fig. 4 is an end elevation of the parts of Fig. 3. Fig. 5 is an end elevation of the movable jaw-member of the name-plate holder. Fig. 6 is a plan view of the said movable jaw-member. Fig. 7 is a front elevation of the said movable jaw-member.

Having reference to the drawings, at 1, Fig. 1, is the frame or housing of a printing-head, which frame or housing will in practice be combined with suitable means for supporting and operating the printing-head. Within the printing-head a set of printing-wheels 4, 5, 6, 7, 8 and 9 is arranged. The group of wheels 4 is adapted to be employed in printing the case number of a lot of shoes. The wheel 5 may be used for printing names or the like, and the remaining wheels may be used for printing sizes and widths. The respective wheels are individually settable to bring the print-

ing characters thereof to the printing line 55 as desired. The particular provisions for setting the same are not material. Various means of setting printing wheels in stamping, marking and numbering machines are known in practice. It therefore is unnecessary to show or describe such provisions.

Referring to the wheel 5, the said wheel carries dies 5^a, 5^b, 5^c, constituting trade-plates, each bearing appropriate printing characters. In Fig. 3 various names or 65 terms employed in the art in connection with shoes appear on the dies. For the reception of the dies, recessed seats 5^e, 5^f, 5^d, are formed upon the wheel 5 at its periphery, in alternation with longitudinally-extending dovetailed ribs 24, 24, etc. The dies are formed with beveled lips to fit under the overhanging side-portions of the ribs, as shown in Fig. 4, making the dies themselves partly dovetailed. The die 5^b 70 is fitted between two ribs 24, 24, which are located at the opposite sides of its seat 5^d, its lips being engaged by the over-hanging side-portions of such ribs. It is inserted or removed by being slid lengthwise between 75 the said ribs. A drawback or disadvantage in connection with a die held in place in this manner, when the wheel on which it is mounted is located intermediate other printing-wheels as in Fig. 1, is that the printing-head must be dismantled and the printing-wheels disassembled, for the purpose of 80 enabling such die to be replaced by another. This renders it inconvenient to change the die. To avoid this inconvenience in the 85 case of the remaining dies carried by wheel 5, ribs are dispensed with at alternate intervals between seats for dies, and in lieu thereof headed screws 5^e, 5^f, are employed. The threaded stems of these enter holes 90 which are tapped radially in the body of the wheel at the places where the ribs are omitted, and their heads occupy the spaces between the adjacent dies. The said screw-heads are accessible at the exterior of the 95 wheel for the purpose of operating the screws. Each screw-head bears by the under side of its head, which is beveled, against the inclined sides of the contiguous lips of the dies between which it is situated, thus 100 forcing the other lips of the said dies under the overhanging sides of the adjacent ribs, the screw coöoperating with the ribs in hold-

ing the dies in place. By partially unscrewing one of the screws from its hole in the body of the wheel 5, so as to raise its flanged head from the lips upon the dies 5 with which it co-acts, one or both of such dies may be turned out of the seat or seats therefor and removed, and another or others inserted, after which the screw may be tightened up again. This enables the dies 10 to be removed or changed as often as may be required, without any necessity for disassembling the series of printing-wheels as heretofore. It will be observed that each screw 5° engages with a pair of the dies. 15 The printing wheels of stamping, marking, or numbering machines, are ordinarily made with eleven divisions, ten of which bear numerals or other printing characters, and the eleventh thereof is a blank. There 20 are, accordingly, eleven subdivisions of the wheel 5, and eleven dies thereon. The means of securing the dies in place, just described, is shown applied in connection with five pairs of such dies, the eleventh die, which 25 is the odd one, being separately held in place in the manner which has been explained.

My means of holding a name-plate detachably in working position upon a printing-head is shown applied to the printing-head in Figs. 1 and 2, and the movable jaw-member thereof is shown separately in Figs. 5, 6 and 7. A name-plate 25 is shown in place in Figs. 1 and 2. As is well known, a plate of this kind, employed in the relations 30 shown, has a central opening within which the peripheral portions of the printing-wheels work, and through which the type-bearing projections pass, as indicated in Fig. 2, while its marginal portions bear lettering or the like to effect a portion of the printing. I employ a fixed jaw 26, Fig. 2, extending in the direction of the length of the printing-head, at one side of the portions of the printing-wheels which are in 35 position to print, and a movable jaw 27 arranged at the opposite side of the said wheels. The two jaws are shaped to engage with the opposite side-edges of the name-plate and hold the same, being grooved longitudinally as at 27^a, Fig. 5, to receive the flanges 25^a, 25^a, projecting from the name-plate at the said side-edges. By engagement with such side-edges throughout the 40 length of the name-plate, the jaws keep the name-plate from springing or buckling at any point. At the ends of the name-plate 45 the back of the latter is kept by the jaws in contact with the lower ends of the side-

portions of the housing or frame 1. The movable jaw 27 is pivotally hung to the said 60 housing or frame, by screws, one of which is represented at 28 in Figs. 1 and 2, fitting holes 28^a, Fig. 5, also shown by dotted lines in Figs. 6 and 7, in ears or lugs 29, 29, which are formed upon the opposite end-portions 65 of the movable jaw-member. A spring is provided in connection with the movable jaw, such spring acting with a tendency to hold the movable jaw closed. Figs. 1 and 2 show an expanding spiral spring 31 employed for the purpose, such spring being confined in the open-topped socket 32 upon one end of the housing or frame 1. An arm 33 extending forward from the adjacent end of the movable jaw-member projects over 70 this socket, and is acted against by the upper end of a plunger, 34, occupying the upper portion of the socket and pressed upward by spring 31. When it is desired to open the movable jaw to release the plate 80 23, or permit the latter to be inserted, downward pressure is applied by hand to the said arm.

What is claimed is:—

1. In stamping, marking, or numbering 85 machines, the combination with a reciprocating printing-head carrying settable printing-wheels, and a name-plate co-acting with the said printing-wheels in producing the required imprint, of opposite jaws clasping between them the edges of the said name-plate and thereby supporting it upon said printing-head, said jaws relatively-movable to open and close, and a spring to occasion the closing of the jaws upon the said edges. 90

2. In stamping, marking, or numbering machines, the combination with a reciprocating printing-head carrying settable printing-wheels, of a name-plate co-acting with the said printing-wheels in producing the required imprint, a fixed jaw carried by the said reciprocating printing-head at one side of the said printing-wheels grooved to receive and sustain one edge of the name-plate, and a movable spring-actuated jaw 100 upon said printing-head at the opposite side of the said wheels, similarly grooved to receive and sustain the opposite edge of the name-plate. 105

In testimony whereof I affix my signature 110 in presence of two witnesses.

EDWARD B. PARKHURST.
